UNITED STATES PATENT OFFICE.

JOSEPH HOLLENBURGER, OF SHINER, TEXAS.

AIR-COOLING APPARATUS.

1,176,558.

Specification of Letters Patent. Patented Mar. 21, 1916.

Application filed May 25, 1915. Serial No. 30,379.

To all whom it may concern:

Be it known that I, JOSEPH HOLLENBURGER, a subject of the Emperor of Germany, residing at Shiner, in the county of Lavaca and State of Texas, have invented new and useful Improvements in Air-Cooling Apparatus, of which the following is a specification.

The invention relates to an air cooling apparatus, and has for its primary object to provide an apparatus of this character wherein air to be delivered to a room or other inclosure will be treated under the influence of moisture to reduce the temperature thereof without the use of ice, the air being sufficiently cooled for use in preserving food stuff and reducing the temperature within a room or inclosure.

Another object of the invention is the provision of an apparatus of this character wherein the air is filtered so as to remove all foreign matter therefrom, thus rendering it pure prior to its circulation within an inclosure or room for refrigeration or other purposes.

A further object of the invention is the provision of an apparatus of this character wherein the construction thereof is of novel form to insure efficiency and reliability in its operation, the construction being simple, thereby enabling it to be installed at a minimum expense.

With these and other objects in view, the invention consists in the construction, combination and arrangement of parts as will be hereinafter fully described, illustrated in the accompanying drawings, and pointed out in the claims hereunto appended.

In the drawing: Figure 1 is a fragmentary vertical sectional view through an inclosure and the foundation therefor, showing the apparatus constructed in accordance with the invention installed. Fig. 2 is a vertical sectional view through the cooling drum. Fig. 3 is a vertical longitudinal sectional view through the filtering drum. Fig. 4 is a sectional view on the line 4—4 of Fig. 1. Fig. 5 is a fragmentary vertical sectional view through the auxiliary filtering cylinder or drum.

Similar reference characters indicate corresponding parts throughout the several views in the drawings.

Referring to the drawing in detail, A designates generally a portion of an inclosure such as a house or a storage room for

food stuff, and B the foundation therefor. Supported upon the foundation B is an air pump C, which is adapted to be driven from a motor D or any approved type. 60

The cooling apparatus comprises a cooling drum 10 which is arranged at a suitable elevation above the surface of the foundation B and spaced from the air pump C, the said drum being supported by posts 11 which are suitably anchored within the foundation and has arranged beneath the same a water collecting tank 12 provided with an overflow cock 13, while above the said cooling drum is a water spraying device 14, receiving 65 its water supply from any suitable source, the drum being covered with a cloth jacket 15 which is adapted to absorb and become saturated with the water discharged from the spraying device 14 so that the contents 70 of the drum will become cooled thereby, the surplus water from the said device 14 being trapped or caught in the tank 12, which delivers its overflow through the cock 13 to any suitable point. Leading from the air 75 pump C is an air delivery pipe 16, the latter being formed with a coil 17 located within the water tank 12 so as to be submerged in the water contained therein, and this pipe 16 is extended upwardly to the top of the 80 drum 10 and is tapped therein for delivering the air after passing through the coil 17 into the drum. Rising from the coil 17 at diametrically opposite points thereof are 85 vertically disposed perforated air jet tubes 18 which emit air under pressure from the pump C in the direction of the jacket 15 on the drum 10 for cooling the jacket so that the air within the drum 10 will be sustained cool under the influence of the water 90 without the same. 95

Leading from the bottom of the drum 10 downwardly through the foundation B to a determined point below the surface thereof is an air delivery pipe 19, the same being 100 tapped in one end of a cylindrical boiler 20 which is embedded in sand and gravel, as at 21, filling a well 22 formed in the foundation, the boiler 20 being constructed within with foraminous strainer disks 23 which 105 confine therebetween a suitable filtering medium 24, while the spaces 25 between the disks 23 and the ends of the boiler 20 serve as air circulating chambers, the air admitted to the boiler 20 from the pipe 19 being designed to percolate through the filtering 110 medium 24 and is delivered subsequently

to the filtering thereof from the said boiler 20 through a conveyer pipe 26 which is tapped in the opposite end of the boiler and leads to an auxiliary filtering cylinder 27 located above the foundation B at any suitable point. Leading from the auxiliary filtering cylinder 27 is a main 28 having branches 29 which distribute the cool air to the points desired or within the inclosure A for use as a refrigerant or for reducing the temperature within the inclosure. Leading from the pipe 19 at a suitable point between its connection with the drum 10 and the boiler 20 is a by-pass pipe 30 which also 15 communicates with the auxiliary filtering cylinder 27. Both the pipes 26 and 30 are provided with cut-off valves 31 so that the course of the air may be directed through the boiler 20 or directly from the drum 10 20 to the auxiliary filtering cylinder 27 on the setting of the valves 31, as will be clearly apparent.

Arranged on the drum 10 and the auxiliary filtering cylinder 27 are pressure gages 32 which will indicate the pressure of the air within the same, while mounted on the drum 10 is a safety valve 33 which is set to the desired pressure so that on the air exceeding the predetermined pounds pressure 25 the valve will operate to permit the escape of air for reducing the pressure within the drum, the pump C being automatically controlled for the starting and stopping thereof under the action of the pressure of the air 30 within the drum 10 in any suitable manner.

From the foregoing description, taken in connection with the accompanying drawings, it is thought that the construction and manner of operation of the device will be clearly 35 understood, and therefore a more extended explanation has been omitted.

Copies of this patent may be obtained for five cents each, by addressing the "Commissioner of Patents, Washington, D. C."

What is claimed is:—

1. A cooling apparatus comprising an air receiving drum, an absorbent jacket without the drum and covering the same, a water spraying device arranged above the drum for moistening the said jacket, a water collector below said drum and having a coil, means for conveying air under pressure through the coil and into the drum, and means for delivering the air from the drum. 50

2. A cooling apparatus comprising an air receiving drum, an absorbent jacket without the drum and covering the same, a water spraying device arranged above the drum for moistening the said jacket, a water collector below said drum, means for conveying air under pressure through the water collector and into the drum, means for delivering the air from the drum, and means for discharging a portion of the air delivered to the drum onto the jacket exteriorly thereof. 60

3. A cooling apparatus comprising an air receiving drum, an absorbent jacket without the drum and covering the same, a water spraying device arranged above the drum for moistening the said jacket, a water collector below said drum, means for conveying air under pressure through the water collector and into the drum, means for delivering the air from the drum, means for discharging a portion of the air delivered to the drum onto the jacket exteriorly thereof, and means for changing the course of the air delivered from the drum. 70

In testimony whereof I affix my signature in presence of two witnesses.

JOSEPH HOLLENBURGER.

Witnesses:

LUDWIG EDER,
FERDINAND SCHMIDT.
